UNITED STATES PATENT OFFICE.

DAVID GRANT, OF MIDDLEFIELD, CONNECTICUT, ASSIGNOR TO THE LYMAN GUN SIGHT CORPORATION, OF MIDDLEFIELD, CONNECTICUT, A CORPORATION OF CONNECTICUT.

DIE MECHANISM FOR SHAPING GUN-SIGHTS AND OTHER ARTICLES.

1,273,769.

Specification of Letters Patent. Patented July 23, 1918.

Application filed August 6, 1914. Serial No. 855,437.

To all whom it may concern:

Be it known that I, DAVID GRANT, of Middlefield, in the county of Middlesex, and in the State of Connecticut, have invented a 5 certain new and useful Improvement in Die Mechanism for Shaping Gun-Sights and other Articles, and do hereby declare that the following is a full, clear, and exact description thereof.

10 The muzzle or front sights of fire arms which comprise a bead and a dovetail base by which the sight is attached to the gun barrel, as heretofore made was produced by milling. This operation is slow and, therefore, costly. The object of my invention is to enable these gun sights to be made more rapidly and, therefore, more economically, and I accomplish such object by die-pressing or shaping, first providing a blank that 15 roughly is T-shaped in cross section. These sights require to be constructed with the greatest accuracy possible and especially must the dovetail base be made with great accuracy for fitting or adaptation of the 20 sight to the transverse retaining groove in any gun barrel. It is for this reason, and because of the accuracy with which milling may be done, and because of certain practical difficulties in the way of die-pressing, or 25 stamping out such an article, that there has been no departure from the milling method. The value and importance of my invention compared with the old milling method of manufacturing these gun sights will be seen 30 when it is stated that a workman making these sights in accordance with my invention in two hours and thirty-five minutes can turn out as many sights as can be made in eighteen days by the milling method. Not 35 only is there this great advantage in rapidity and economy of manufacture, but the sight itself is better by reason of the condensation or solidifying of the metal due to the dieing operation, and because of the uniformity 40 of the product to a degree not possible with milling.

While my invention has in view the production of gun sights it will be evident that merely by varying the configuration of the 45 dies it is applicable in some of its features to the production of other articles than gun sights. My invention, therefore, consists in means for the production of gun sights or

other articles by the use of dies, substantially as hereinafter specified and claimed. 55

In the accompanying drawings—

Figure 1 is an elevation of a die and work holder for carrying out my invention showing sections of the die-bed and punch;

Fig. 2 is a similar figure in central cross section as taken on the line 2—2 of Figs. 3 and 4;

Fig. 3 is an elevation of Fig. 1 taken at right angles thereto, whereby if either of the views be considered the front the other 65 will comprise a side elevation;

Fig. 4 is a central horizontal cross section through Figs. 1 and 2;

Fig. 5 is a view corresponding to Fig. 3 of the die and work holder in the open 70 position for the reception of the work;

Fig. 6 is a horizontal central cross section through Fig. 5;

Fig. 7 is a perspective view of a blank adapted for the formation of a gun-sight 75 by means of my invention.

Fig. 8 is a perspective view of a completed sight formed from such a blank;

Fig. 9 is a view of the muzzle end of a gun barrel and side view of a gun sight 80 mounted thereon.

Fig. 10 is a detail view of the dies for forming the sight ridge.

Referring to the drawings, in Figs. 8 and 9 particularly, is shown a front sight 10 for 85 fire-arms, of the type which is held in place on the barrel by means of a dovetailed tenon or base 11, on the lower side of the part, inserted tightly in a correspondingly shaped groove 12, in the upper surface of the muzzle end of the barrel of the fire-arm 100. The sight proper comprises a ridge or sight bead 13, formed on the upper surface of the sight block transversely of the dovetailed base or tenon, and therefore longitudinally 95 of the barrel, since the dovetail is fitted crosswise thereof, as shown in Fig. 9. As the sight requires to be mounted absolutely centrally of the barrel of the fire arm or with the sight bead in the vertical plane of 100 the axis or line of aim, and is held by friction in the groove in which it is seated, the utmost degree of accuracy is necessitated in shaping and standardizing the configuration and proportion of the dovetailed sight 105 base, and relative position and construction

of the sight bead. The formation of the sight by means of dies present great difficulties for the mechanism is required to insure such minute fractional uniformity of the measure between angular sides of the dovetailed base that the sights taken at random will fit the grooves of firearms indiscriminately, with substantially the same frictional hold at the same point whereby the sight when inserted to the same central position may be held with invariable clutching effect. Also the formation of the angular surfaces of the dovetail involve lateral thrust both upon the dies and the work in one direction only, and is impossible of counteraction by the ordinary devices of power presses.

My appliances for producing this class of work comprise a two-part holder in which the work is clamped and the forming dies are guided and confined, and centralized in action, and the lateral strains of operation render reactionary and counter-resistant. The holder comprises the two parts 14 and 15 hinged together at one side by means of the respective hinge ears 16 and 17, formed thereon and the hinge pin 18, upon which both parts are swung in the operation of being opened or closed. In the opposite edge of one of the parts 14 are hinged the swivel nuts 19, in which are screwed suitable clamping screws 20 adapted to be swung into slots 21, in the edge of the opposite part and their heads 22, screwed down firmly thereon to clamp the sections together in the closed position, as shown in Figs. 1 and 3.

Centrally in the section 15, is a recess or seat 23, for the reception of the die or dies for holding the work. In Figs. 5 and 6 is shown the die 24, for seating the sight blank in the construction of the sight ridge while Figs. 2 and 4 show the dies 30, for holding the blank by means of the sight ridge, in the operation of shaping the dovetail. These dies are held in their seat by the screws 31 inserted through the bottom of the holder. In the interior face of the said part 15 in the plane of the recess, a groove is formed extending from one edge of the holder to the other parallel with the hinge and providing separate guideways 241 on the respective sides of the recess 23, for the reception of the respective dies 25, in alignment with each other and the center of the recess. The inner ends of the dies have the configuration of the article to be shaped between them which in Figs. 2 and 4 is the dovetail of the sight, the dies in such case having ends cut to the angle of the dovetail, as shown. The opposite ends of the dies are cut square with their length, for impact with the punch head and die bed 26 and 27, of a power press, or other mechanism for applying pressure for forcing the

dies together and upon the work. The dies forming the sight ridge, which in cross section comprises a cylinder connected to the base by a neck, as shown in Fig. 8, will obviously be formed of corresponding shape at the ends which engage the sight or bead but otherwise do not differ in any respect from dies 25 shown in Fig. 2.

In the opposite section 14 of the holder a cavity 28 is provided for seating an anvil or resistance block 29, centrally registering with the seat 23, and adapted to bear upon the sight blank to resist the lateral strain imposed by the die thereon. A set-screw 271 is screwed into the section of the holder back of the resistance block in engagement therewith and by means of which the block may be forced or clamped tightly against the work.

A pair of screw threaded studs 32, are screwed into each end of each of the holder sections, with their ends projecting to form adjustable stop elements which by engagement with the punch head 26 and die bed 27 of the press serve to gage the space between said parts at the limit of the stroke of the punch, and to determine the amount of the action of the forming dies as hereinafter fully specified. Set screws 33, are provided for securing these stops in position when adjusted by binding action against their sides. In the operation of this mechanism, two distinct actions are involved in connection with the formation of the respective independent features of the sight shown and described, viz., the sight bead, and dovetailed base, but which involve substantially the same procedure.

Considering first the formation of the sight bead, the die 24 is placed in the recess 23, and the sight blank 331 is set into the groove 34, in the die, which is of the width to receive it loosely, as shown in Fig. 5, the flat side of the blank being placed in contact with the die with the sight bead part projecting above the die transversely in the plane and path of movement of the two shaping dies received and guided in the guideways of the holder. The ends of the said forming dies which face each other are shaped to conform to the finished shape of the sides of the sight bead, but otherwise do not differ from the representation of the forming dies in Fig. 2, and they are omitted from Fig. 6, which shows the blank in position to form the sight bead, but it will be understood the forming dies operate thereon as described with reference to Figs. 2 and 4, hereinafter specified. The opposite half or section 14 of the holder next being closed upon the part 15 and the two sections locked together with the forming dies received in their guideways the holder may then be placed upon the press bed as shown in Fig. 1, and the punch-head brought down upon

it. It is to be understood that the forming dies prior to the operation of shaping the part and when in contact with the work together register a greater length between 5 their outer ends than the length over all between the ends of the adjustable stop studs, said excess space between the ends of the forming dies representing the amount of movement which the dies are to make to 10 shape the work and which may be determined by the requisite adjustment of the stops, as shown in Fig. 3. The forming dies are passed over the base part of the blank from which the sight base is formed until 15 they contact with the sight ridge, at which point they will remain at rest until pressure is brought to bear upon them to compress and mold the sight ridge into the true form of the sight bead which is that shown in 20 Figs. 4 and 8, or its configuration after receiving the compact of the dies.

It will be observed that through the provision of suitable clearance space 36 the sight blank is not held rigidly in its seat in the 25 die 24, but can readily move vertically therein under the action of the forming dies, thus "floating" as it may be termed, into the proper position to centralize itself between the respective dies and receive equal 30 pressure and impact from each and form equal depths of cut on the respective sides of the block. In this action, which is of the utmost importance in the standardization of the product, the lateral strain on the 35 work is in the direction to force the blank down upon its seat in the holding die and the resistance block is not required to press against the blank in the shaping process, and in the production of this feature of the 40 sight its use can be dispensed with. In other words since the tendency under the pressure of the bead-forming dies is not to force the metal of the blank toward the holding die 29, the latter need not be present 45 during the action of the dies for forming the bead.

In the operation of forming the dovetailed base of the sight, employing the holding dies 30, between which the finished 50 sight-bead is placed lengthwise with respect to the stroke of the forming dies as shown in Fig. 2 and Fig. 4, with a base of the blank in the line of action of the forming dies 25, as shown in Figs. 2 and 4, it is necessary 55 to make use of the resistance block or anvil 29 to oppose the lateral strain on the work by the angularity of the ends of the dies which in operation tend to force the blank in the direction of the opposite part of the 60 holder. With the anvil in place and screwed tightly against the work the forming dies may then be forced upon the blank base to form the dovetailed impressions therein corresponding to the angular ends of the dies, 65 as shown in Fig. 2. In this process the work

is enabled to move in its seat by means of the clearance space 37 provided therefor, and centralize itself with reference to the shaping dies and the stops of the holder to insure equal depths of the impressions in the 70 respective sides of the dovetail, and accurate intermediate measurement between them. The stroke of the press should be adjusted to close the punch and press bed slightly nearer together than the length over all between 75 the ends of the stops in order to insure the full stroke of the forming dies and eradicate all possibility of lost motion in the parts. Such slight excess movement of the punch is made possible by the slight corresponding yielding action or spring of the press frame which lacks absolute rigidity and possesses sufficient elasticity for such purpose. The completion of the dovetail indentations of the base will result in the 80 production of a finished sight base as shown in Fig. 8.

The anvil block as shaped to assist in the production of the dovetail of the base is preferably formed with a central recess 38, 90 as shown in Figs. 2 and 4, which restricts its bearing to its ends. The resisting effect of the anvil is required chiefly upon the ends of the base or those portions on the sides of the sight bead and which are of 95 much less thickness than the central depth of the block through the bead. The tendency of the action of the dies is to draw down upon said thin portions and fracture their ends and otherwise distort the blank. 100 The counteracting pressure should be directed to said ends and concentrated thereon and this I effectually accomplish by relieving or forming a chamber in the central zone or field of the resistance block as shown 105 so that it bears wholly upon the said thin parts of the sight base.

By the use of the holder the lateral strain on the dies is counteracted and their action is confined to a predetermined field while 110 the work is held to the plane of such action in resistance to lateral strain and centralized between the dies resulting in a finished product superior in quality to milled work and at a vastly reduced cost. The holder with 115 its stop comprises a gage which mathematically insures the precise and invariable length of stroke of the dies and infinitesimal accuracy and uniformity of the proportions of the stamped parts and their standardization while the provision for the "floating" or self-centering movement of the work 120 secures the positioning of the sight bead exactly central of the base whereby when it is brought into coincidence with the line of 125 sighting when the sight is driven into its seat in the gun barrel, the frictional hold of the base therein will always be the same in sights indiscriminately selected from a lot, and any sight produced by the systems 130

can be relied upon to fit perfectly upon any gun barrel which has a sight seat calculated for it, simply as the parts are furnished to the trade, and without further manipulation.

A press of ordinary construction can be used in the practice of my invention and my invention can also be practised in a specially organized machine or press.

10 Having thus described my invention what I claim is—

1. As an improvement in dies for die-shaping, the combination of oppositely and simultaneously moving shaping dies, and a seat for the work to be shaped situated between the opposing faces of the dies, said seat permitting movement of the work in the direction of movement of the dies.

2. As an improvement in dies for die-shaping, the combination of a work holder, two dies movable toward each other and movable toward the work in the holder, and means to limit the movement of the dies toward the work consisting of relatively stationary and moving surfaces that contact in the direction of the movement of the dies.

3. As an improvement in dies for die-shaping, the combination of oppositely and simultaneously moving dies, a seat for the work between said dies and an anvil or support for a face of the work that lies in a plane parallel with the direction of movement of the dies, said seat and anvil face permitting movement of the work in the direction of movement of the dies, and a clearance space being provided in the direction in which the work moves with the dies.

4. As an improvement in dies for die-shaping, the combination with the dies of a two-part holder having guideways in which the dies are seated and adapted to travel, and a seat for the work or article to be shaped between the dies, means on opposite sides of the holder that engage and

cause movement of the dies toward each other; stopping mechanism for limiting the movement of the dies upon the work acting upon said die-engaging means and clamping means for securing the respective parts 50 of the holder together.

5. As an improvement in dies for die-shaping, the combination with the dies of a two-part holder having guideways in which the dies are seated and adapted to travel, and a seat for the work or article to be shaped between the dies, adjustable stops carried at the ends of the die-holder for limiting the movement of the press die upon the forming dies upon the work, 60 means upon opposite sides of said holder that engage said dies and cause them to move toward each other, and also engage said stops, and clamping means for securing the respective parts of the holder together.

6. As an improvement in dies for die-shaping requiring standardizing and centralization, the combination of a die-holder having a guideway throughout its 70 length, forming dies fitting and adapted to slide in the guideway, a guiding seat intermediate of the ends of the holder for receiving the work, having a clearance space for permitting movement of the work in 75 the line of the stroke of the dies, and adjusting stops carried at the ends of the holder to serve as contact abutments, respectively, for the punch and press bed to regulate and determine the length of the stroke 80 of the dies, whereby the work is rendered self-centering in relation to the action of the dies.

In testimony that I claim the foregoing I have hereunto set my hand this twenty-eighth day of July, A. D. 1914.

DAVID GRANT.
